UNITED STATES PATENT OFFICE.

HENRY J. CARY, OF SAUKVILLE, WISCONSIN.

LIQUID-FUEL BURNER.

Application filed April 30, 1918, Serial No. 231,582. Renewed November 27, 1922.

To all whom it may concern:

Be it known that I, HENRY J. CARY, a citizen of the United States, and resident of Saukville, in the county of Ozaukee and 5 State of Wisconsin, have invented new and useful Improvements in Liquid-Fuel Burners, of which the following is a description, reference being had to the accompanying drawings, which are a part of this specification. 10

My invention relates to liquid fuel burners and more particularly to a burner using kerosene as fuel.

In kerosene burners it is necessary to provide a means for vaporizing the fuel previous to its ignition in the burner. I am aware that it has been proposed to place the vaporizer directly above the burner or to provide an annular vaporizing conduit 15 rounding the burner head, but in these constructions the vaporizer is heated to such a high temperature as to "crack" the constituents of the fuel and produce an inefficient mixture. To obviate this difficulty I have 20 provided a new arrangement and novel combination of parts whereby the vaporizer is only subject to a portion of the heat generated by the burners so that just enough heat is imparted to the fuel to cause efficient vaporization. 25

The invention further consists in the novel parts and combinations of parts hereinafter described.

In the drawings:

35 Fig. 1 is a plan view of the burner embodying the invention, parts being broken away and parts being shown in section;

Fig. 2 is a section taken on the line 2—2 of Fig. 1;

40 Fig. 3 is a section taken on the line 3—3 of Fig. 2;

Fig. 4 is a detail section taken on the line 4—4 of Fig. 2.

In the drawings numeral 5 designates the 45 circular burner body having a mixing or expansion chamber 6 therein, and provided with a burner head in communication with said chamber.

The mixing chamber 6 is formed by the 50 circular wall 7 of body 5, a channel 8 extending from one side of the body to and beyond the center of the chamber, said channel being formed by partitions 9 extending inwardly from the wall 7, a deflector 10 disposed adjacent the outlet 11 of the channel 55 8 to divide the mixture passing through the

channel 8 into two streams within the mixing chamber and thus provide for proper flow of the mixture. The channel 8 is open at its inlet end 12 to admit air and the vaporized fuel. The top 13 of the mixing chamber is provided with a plurality of radially disposed openings 14 and other openings 15 adjacent the channel 8 to conduct the mixture from said chamber to the burner head. 60 65

The burner head is formed by the top of the body 5 and a removable plate or cap 16. It is formed by an upwardly and outwardly inclined flange 17 on the body having radially disposed inwardly extending upwardly inclined projections 18 and the cap 16 being spaced from the top 13 by short lugs 18', to form a passageway 19, and having radially disposed outwardly extending 70 upwardly inclined projections 20 which are disposed in the recesses 21 formed by the projections 18 but which are spaced from said projections to form a circular corrugated passage or series of passages 22 between the flange 17 and cap 16 through 75 which the fuel passes from the passageway 19.

The burner may be supported in any suitable manner as by an upright 23 secured to 80 a centrally disposed lug 24 on the body 5.

The vaporized fuel is introduced into the mixing channel 8 by means of a spray nozzle 25, the passage of fuel therethrough being controlled by a needle valve 26 adjustably 85 mounted in a threaded plug 27 secured adjacent the nozzle.

In the construction thus far described the fuel from the nozzle 25 and the air enter the channel 8 and are partially mixed and then 90 pass into the divided mixing chamber 6 from whence the mixture passes through the openings 14 and 15 into the passageway 19 and thence through the passage 22 and is 95 then ignited and burns above the burner head. 100

I do not claim that the construction above described is original with me, but I illustrate it and describe it for the purpose of showing a construction which is capable of 105 use in combination with the new and novel parts now to be described which parts it will be understood may be used in combination with any suitable form of mixing chamber and burner head.

My invention resides in the vaporizing means and the means for heating said vapor.

izing means and their combination with the burner.

The vaporizing means consists of a vaporizing tube 28 disposed at one side of the body 5 and secured thereto by a clip 29 and screws 30, said tube being connected at its lower end 31 to a fuel supply pipe 32. This tube 28 extends upwardly along side the burner head and thence downwardly, the spraying 10 nozzle and needle valve previously described being located adjacent the end 33 of said tube.

Clip 29 has one end projected beyond the body 5, as shown clearly in Figure 3 of the 15 drawing, and thereby provides a free end forming a spring clamping means which can be adjusted to the vaporizing pipe, either tight or loose as desired, by manipulating the single screw 30 which engages said free end.

20 The means for heating the vaporizing means consists of a portion of the heat from the burner which is diverted from the burner head against the tube 28 by means of a deflector. This deflector consists of a hood 25 formed over a portion 34 of the burner head and having a side opening 35 adjacent the tube 28 formed with a vertical straight portion having integral thickened walls for a portion of its length and so that the burning 30 fuel of this segregated portion of the burner furnishes sufficient heat to the tube 28 to cause efficient vaporization of the fuel passing therethrough. The hood is formed by a top plate 36, an inner side wall 37, an end 35 wall 38 and an end wall 39. The top plate 36 extends inwardly over the portion 34 of the burner passage 22 and the side wall 37 is formed by a flange depending from this top plate and disposed adjacent the inner 40 side of the burner passage 22. The end wall 38 is formed by a flange depending from the end of the plate 36 and has an outwardly extending curved portion 40 disposed adjacent the tube 28. The end wall 39 is one end 45 of a partial ring section 41 which is secured to the end portions of the top plate 36. The ends of the wall 37 are spaced from the inner

ends of the walls 38 and 39 to form channels 42 to allow air to pass inside the hood adjacent the flange 37. The ring section 41 has 50 an upwardly and inwardly inclined wall 43 disposed adjacent the burner passage 22 and a continuous groove 44 seated on the upper outer edge of the body 5.

With this construction the burning fuel 55 of that portion of the burner head which is covered by the hood has its heat deflected outwardly against the tube 28 which is heated sufficiently to produce a more efficient vaporization of the fuel as it passes to the spray 60 nozzle 25 than would be the case were the tube 28 subjected to the whole or a greater portion of the heat from the burner.

I am aware that the details of construction herein shown and described are subject 65 to modification and change, but such changes as come within the scope of the appended claims I deem to be within the spirit of my invention.

What I claim as my invention is:

In a device of the class described, a burner-head, a vaporizing-pipe, and a heat deflecting means mounted on the burner-head to deflect a portion of the heat from the burner to the vaporizing-pipe, said vaporizing-pipe being formed with a vertical straight portion having integral thickened walls for a portion of its length to provide bosses adapted to be positioned below the plane of the body-portion of the burner, one 70 of said bosses having formed therein a spray-nozzle and the other a threaded opening to receive a packing-plug, and a bowed holding-clip partially surrounding the vertical straight portion of the vaporizing-pipe and 75 secured on opposite sides thereof to the body-portion of the burner by screws, whereby the vaporizing-pipe can be bodily adjusted vertically with respect to the burner and its heat deflector by loosening the screws of the 80 holding clip.

85 In testimony whereof, I affix my signature.

HENRY J. CARY.
